Attorney.

UNITED STATES PATENT OFFICE.

DONALD McLEOD, OF LANG LANG, CRANBOURNE, VICTORIA, AUSTRALIA.

BARBER'S APRON.

1,261,575.

Specification of Letters Patent.

Patented Apr. 2, 1918.

Application filed August 10, 1917. Serial No. 185,501.

To all whom it may concern:

Be it known that I, DONALD McLEOD, a subject of the King of Great Britain and Ireland, and a resident of the postal town 5 of Lang Lang, in the shire of Cranbourne, county of Mornington, State of Victoria, Commonwealth of Australia, (whose post-office address is the postal town of Lang Lang,) have invented certain new and useful Improvements in and connected with 10 Barbers' Aprons, of which the following is a specification.

This invention relates to the cutting of human hair and has for its object to provide 15 means for collecting the removed hair as it falls from the head in order that it may not fall to the ground according to the present practice.

The present practice of surrounding the 20 shoulders of a person with a cloth covering is objectionable as the hair as it is removed or cut drops onto the covering and from there to the floor, the hair which remains upon the covering being shaken off when the 25 covering is removed. This is insanitary and also entails labor and expense in continually washing the covering. The periodical sweeping of the floor to remove the hair also entails labor and in addition causes dust 30 and hair to rise thereby contaminating the atmosphere.

According to the present invention I provide 35 a light and durable cape or covering adaptable to fit any person and which can be folded into a small space when not in use. This cape which can be repeatedly used, saves the necessity of frequently washing the covering. It not only protects the shoulders from the falling offcuts of hair, but is 40 also adapted to discharge them into a gutter which surrounds its lower edge. Thus the hair does not drop onto the floor and the work of sweeping and consequent pollution of the atmosphere is obviated. With the 45 cape a removable collar of cloth or other flexible material is used to surround its upper end and the neck of the person to which it is applied. This collar may be washed or a new one used after each person. Provision 50 is also made in one form of the in-

vention for removing the front portion of the gutter to permit of ingress to and egress from the chair, in which the subject sits. Other features of the invention will be fully understood from the following description, 55 and defined in the appended claims.

Referring to the drawings which form a part of this specification:—

Figure 1 shows a plan of a cape composed of a series of metallic or other segments. 60 The cape is shown expanded as when in use.

Fig. 2 is a front elevation of Fig. 1.

Fig. 3 is a plan of a gutter used with the cape seen in Figs. 1 and 2.

Fig. 4 is a front sectional elevation of the 65 cape shown in Figs. 1 and 2 situated in position above the gutter seen in Fig. 3. A collecting box is also shown in position beneath a chute through which the hair is discharged from the gutter.

Fig. 5 is a front view partly in section of a preferred embodiment of the invention in which the cape is made of a suitable flexible material the gutter being integral with or attached to its lower edge.

Fig. 6 is a perspective view of an inner rigid collar.

Fig. 7 is a similar view of an outer flexible collar.

Fig. 8 is a perspective view showing the 80 invention (as illustrated in Fig. 5) in use.

The invention includes a collapsible or foldable cape which may be formed as seen in Figs. 1, 2, and 4 from a series of metallic or other rigid connected segments 2, or, as 85 seen in Figs. 5 and 8, it may consist of a single length of flexible or semi-flexible material 3. This may be of fabric, leather, or any other suitable material of such a character that it may be rolled or folded up 90 when not in use, but has sufficient rigidity to maintain its correct shape when in operative position. In all cases the cape preferably has a smooth or glazed outer surface so that hair falling thereupon immediately glides 95 downwardly and off the cape. The front meeting ends 4 of the cape are connected together by means of suitable fasteners 6 and when in use it assumes a substantially conoidal form, the base of the cape being 100

preferably elliptical in plan to clear the shoulders and permit movement of the arms of the wearer. The neck hole 5 is large enough to freely pass the neck of any wearer.

When the cape is of the segmental construction seen in Fig. 1 the two front segments may be provided at their upper ends with flaps 7 which are adapted to fall inwardly upon the chest of the wearer and permit free movement of the neck and chin.

To protect the neck against the upper edges of the connected segments an inner rigid collar, such as seen in Fig. 6, is used. This is connected at 8 and has inclined sides 9 forming a gullet 10, into which the upper edges of the segments pass. An upper rounded edge 11 is thus presented to the neck of the wearer.

With both types of cape an outer flexible collar such as seen in Fig. 7 is used. This is of cloth or other suitable flexible material and is provided with an inner vertical fold 12 which is tucked around the neck and inside the garment collar of the wearer and an outer inclined fold 13 which passes over the outside of the inner rigid collar and the cape as seen in Fig. 8. This flexible collar prevents hair falling down the wearer's neck and may be removed and washed or replaced by a new one after each use.

Attached to the chair 14 by any suitable means such as extensions or supports 15 (Figs. 3 and 4) is an annular gutter 16 which is preferably formed with inclined sides 17, the inner side conforming to the inclination of the cape. The said gutter is provided with a removable front portion 18 (Fig. 3) which fits within and is supported by the fixed portion of the gutter.

Instead of the gutter 16 being attached to the chair it may be carried by the cape as seen in Figs. 5 and 8. In this case the cape and the gutter are formed of a suitable flexible material as before mentioned, the whole being capable of rolling up or collapsing when not in use.

Through the bottom of the gutter and at the rear thereof is an opening 19 from which leads a chute 21. This may, if desired, be detachable. Beneath the chute a collecting box or receptacle 22 is placed.

When not in use the cape may be folded or rolled into a small space. When a hair cutting operation is to be performed with the embodiment shown in Figs. 1 to 4 the customer or subject enters the chair and the removable front portion 18 of the gutter is placed in position. The cape is then passed around his shoulders, the meeting ends being connected together by the fasteners 6 and the lower edge overlapping and resting upon the inner side of the gutter. The in-

ner rigid collar is then passed over the upper edge of the cape and the inner vertical fold 12 of the outer flexible collar is tucked around the neck of the wearer, the outer inclined fold 13 passing outside the inner collar and surrounding the upper portion of the cape. The hair offcuts fall upon the cape and from there into the gutter. When the hair cutting operation is completed the offcuts are swept around the gutter to the opening 19 at the rear thereof and fall through the chute 21 into the collecting receptacle 22. The cape and the front portion 18 of the gutter may then be removed and the subject is free to pass out of the chair.

When the flexible cape seen in Figs. 5 and 8 is used, the subject sits in the chair and the cape and gutter are passed around the back of the chair and fastened at the front of the wearer as shown. The inner fold 12 of the flexible collar is then tucked around the neck of the wearer and the inclined fold 13 overlaps the top of the cape as before.

It will be seen that the invention provides an arrangement which is sanitary and convenient and dispenses with the necessity of sweeping up the hair from the floor and the washing entailed by the use of the ordinary calico or like covering at present in use.

It will be obvious that various modifications and alterations of the constructions illustrated and described may be effected without departing from the spirit and scope of the invention as defined by the appended claims.

Having now described my invention, what I claim as new and desire to secure by Letters Patent is:—

1. A device of the class described comprising a conical apron consisting of a plurality of collapsible sections the ends of said apron overlapping, means for securing the overlapping ends of the apron, a fixed gutter at the bottom of the apron, means for rigidly supporting the gutter, a chute depending from the gutter, and a detachable collar fitting over the upper edge of the apron.

2. A device of the class described comprising an apron, a fixed gutter open at the front and located at the bottom of the apron, a detachable section at the front of the gutter, the opposite ends of the detachable section overlapping and fitting in the open ends of the fixed section, and a chute communicating with the gutter.

3. A device of the class described, comprising an apron formed of collapsible sections, the ends of said apron overlapping, means for connecting the overlapping ends of the sections, flaps at the upper ends of

the apron, a fixed gutter surrounding the lower end of the apron, and means for permanently supporting the gutter.

4. A device of the class described comprising an apron, the ends of which overlap, means for fastening the overlapping ends of the apron, an inner detachable collar to engage the upper edge of the apron, an outer

collar fitted over the inner collar, a rigid gutter section open at its front and located 10 at the bottom of the apron, and a front detachable gutter section the ends of which fit in and register with the open ends of the fixed gutter section.

In testimony whereof I affix my signature. 15
DONALD McLEOD.
